Primary Examiner — Katherine Glennon*(74) Attorney, Agent, or Firm* — Holtz, Holtz & Volek PC(57) **CLAIM**

The ornamental design for a wrist watch, as shown and described.

DESCRIPTION

FIG. 1 is an enlarged-scale front, right side, bottom perspective view of a wrist watch showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front elevational view thereof, showing a state in which this article is electrified; and,

FIG. 9 is a perspective view thereof, showing the wrist watch in an environment of use.

The broken line circles shown in FIGS. 1, 4-7, and 9 illustrate portions of the wrist watch that from no part of the claimed design. In FIG. 9, the broken lines showing a watchband illustrate environmental structure only and form no part of the claimed design.

1 Claim, 8 Drawing Sheets(56)
